RAILWAY TRAFFIC CONTROLLING APPARATUS

John M. Pelikan, Crafton, Pa., assignor to The Union Switch & Signal Company, Swissvale, Pa., a corporation of Pennsylvania

Application January 25, 1930, Serial No. 423,347
Renewed May 27, 1933

21 Claims. (Cl. 246—160)

My invention relates to railway traffic controlling apparatus, and particularly to apparatus of the type involving a railway switch and a signal governing traffic over the switch.

5 One feature of my invention is the provision of novel and improved means for preventing operation of the switch when the signal gives a proceed indication and a train is approaching the signal.

10 I will describe one form of apparatus embodying my invention, and will then point out the novel features thereof in claims.

The accompanying drawing is a diagrammatic view showing one form of apparatus embodying 15 my invention.

Referring to the drawing, the reference characters 1 and 1^a designate the track rails of a stretch of main track A, which rails are divided by insulated joints 2 to form a main or detector section U—V, and an approach section W—Y, these sections being separated by an intervening 20 section Y—U the purpose of which will be explained hereinafter. The main section U—V is provided with a switch B leading into a side track C. Traffic moving toward the right through the main section U—V is governed by two signals S¹ and S² controlled in part by contacts 8 and 9 of the usual home relays H¹ and H², which relays are usually controlled from a distant point 25

such as an interlocking tower or a dispatcher's office. The control of these relays forms no part of my present invention, and, consequently, the controlling circuits have not been illustrated in the drawing. The switch B is provided with an 30 operating mechanism or switch machine D which is also controlled in part from the same remote point through the medium of circuits which are represented in the drawing by the reference character G.

35 Each track section U—V and W—Y is provided with the usual track circuit, comprising a battery 3 connected across the rails at one end of the section and a track relay T¹, T², respectively, connected across the rails at the other end of the section. An auxiliary relay E and a source of current 4 are connected in series around one of the insulated joints 2 between the main section U—V and the intervening section Y—U, so that relay E is normally deenergized, but becomes energized when this joint is bridged by a train. The intervening section Y—U is so short that no car can occupy this section without releasing one or both of the track relays T¹, T².

40 The reference character M designates the usual approach locking relay, having a front contact 14

included in the operating circuits for the switch mechanism D, so that the switch B cannot be operated unless this relay is energized. The relay M is provided with a pick-up circuit which passes from terminal X of a suitable source of current, through front contact 5 of the auxiliary relay E, back contact 6 of track relay T¹, and the winding of relay M to terminal O of the same source of current. It follows that when relay M is deenergized, it cannot again be energized 10 unless relay E is energized at the same time that relay T¹ is deenergized. That is to say, relay M cannot become energized until a car bridges the insulated joints 2 between sections Y—U and U—V. Relay M is provided with the usual stick 15 circuits, one of which includes its own contact 11 and front contact 10 of track relay T², and another of which includes contact 11 as well as back contacts 12 and 13 of the signal relays H² and H¹, respectively. These stick circuits form 20 no part of my present invention. Relay M will also usually be provided with other pick-up circuits to permit emergency operation of this relay, but these circuits, likewise, constitute no part of my present invention.

Assuming that one of the signals S¹ or S² has been cleared to permit a train moving toward the right to enter section U—V, then when such train enters the approach section W—Y, it will open one of the stick circuits for relay M at contact 10 of track relay T². The other stick circuit will of course be open at contact 12 or 13, and so relay M will become deenergized. Then when the train bridges the insulated joints at point U, relay E will be energized and relay T¹ will be deenergized, so that the pick-up circuit for relay M will be closed, and this relay will become energized to release the approach locking for the switch B.

One important feature of my invention lies in 40 the fact that momentary interruption of the supply of track circuit current for the main section U—V cannot result in false energization of relay M, as may be the case when the pick-up circuit for this relay is controlled only by a back contact of the track relay for such section.

In order to check the operation of the relay E, a back contact 7 of this relay may be included in the operating circuits for signals S¹ and S².

Although I have herein shown and described 50 only one form of apparatus embodying my invention, it is understood that various changes and modifications may be made therein within the scope of the appended claims without departing from the spirit and scope of my invention.

Having thus described my invention, what I claim is:

1. In combination, a section of railway track containing a switch, an approach locking relay, means for preventing operation of said switch unless said relay is energized, a track circuit including a track relay connected across the rails of said section, an auxiliary relay and a source of current connected in series across an insulated joint at one end of said section, and a pick-up circuit for said approach locking relay including in series a back contact of said track relay and a front contact of said auxiliary relay.
2. In combination, a section of railway track containing a switch, an approach locking relay, means for preventing operation of said switch unless said relay is energized, a track circuit including a track relay connected across the rails of said section, an auxiliary relay and a source of current connected in series across an insulated joint at one end of said section, a signal governing traffic through said switch and controlled in part by a back contact of said auxiliary relay, and a pick-up circuit for said approach locking relay including in series a back contact of said track relay and a front contact of said auxiliary relay.
3. In combination, a section of railway track containing a switch, an approach locking relay, means for preventing operation of said switch unless said relay is energized, a track circuit including a track relay connected across the rails of said section, an auxiliary relay and a source of current connected in series across an insulated joint at one end of said section, a stick circuit for said approach locking relay controlled in part by a train approaching said section, and a pick-up circuit for said approach locking relay including in series a back contact of said track relay and a front contact of said auxiliary relay.
4. In combination, a main section of railway track containing a switch, an approach locking relay, means for preventing operation of said switch unless said relay is energized, a track circuit including a track relay connected across the rails of said section, an approach track section separated from said main section by an intervening section and provided with a track circuit including a track relay, said intervening section being so short that no car can occupy it without opening the track relay of either the main or the approach section, an auxiliary relay and a source of current connected in series around an insulated joint separating said main section from said intervening section, a pick-up circuit for said approach locking relay including in series a front contact of said auxiliary relay and a back contact of the track relay for the main section, and a stick circuit for said approach locking relay including a front contact of the track relay for said approach section.
5. In combination, a main section of railway track containing a switch, an approach locking relay, means for preventing operation of said switch unless said relay is energized, a track circuit including a track relay connected across the rails of said section, an approach track section separated from said main section by an intervening section and provided with a track circuit including a track relay, said intervening section being so short that no car can occupy it without opening the track relay of either the main or the approach section, an auxiliary relay and a source of current connected in series around an insulated joint separating said main section from
- said intervening section, a signal governing traffic through said switch and controlled in part by a back contact of said auxiliary relay, a pick-up circuit for said approach locking relay including in series a front contact of said auxiliary relay and a back contact of the track relay for the main section, and a stick circuit for said approach locking relay including a front contact of the track relay for said approach section.
6. In combination, a section of railway track containing a switch, an approach locking relay, means for preventing operation of said switch unless said relay is energized, a track circuit including a track relay connected across the rails of said section, a normally deenergized auxiliary relay arranged to be momentarily energized by a train entering said track section, and a pick-up circuit for said approach locking relay including in series a back contact of said track relay and a front contact of said auxiliary relay.
7. In combination, a main section of railway track containing a switch, an approach locking relay, means for preventing operation of said switch unless said relay is energized, a track circuit including a track relay connected across the rails of said section, an approach track section extending from said main section and provided with a track circuit including a track relay, a normally deenergized auxiliary relay arranged to be momentarily energized by a train passing from said approach section to said main section, a pick-up circuit for said approach locking relay including in series a front contact of said auxiliary relay and a back contact of the track relay for the main section, and a stick circuit for said approach locking relay including a front contact of the track relay for said approach section.
8. In combination, a stretch of railway track including a switch and an insulated joint, a relay and a source of current connected in series across said insulated joint, a stick relay having a pick-up and a stick circuit one of which is controlled by said first relay and the other of which is controlled by other means, and means controlled by said stick relay for controlling said switch.
9. In combination, a stretch of railway track including a switch, a normally open track circuit including a portion of the rails of said stretch, a source of current and a relay adapted to be energized as a train traverses said stretch of railway, locking means controlled by traffic conditions for at times preventing the operation of said switch, and means effective when the relay of said track circuit is energized for putting said locking means into condition to permit the operation of said switch.
10. In combination, a stretch of railway track including a switch, a normally open track circuit for said stretch including a source of current and a relay connected around an insulated rail joint, locking means controlled by traffic conditions for at times preventing the operation of said switch, and means effective when the relay of said track circuit is energized for putting said locking means into condition to permit operation of said switch.
11. In combination, a stretch of railway track including a switch, an approach locking relay, means for preventing operation of said switch unless said relay is energized, a normally open track circuit having a relay and a current source and including a portion of the track of said stretch which circuit is adapted to energize its relay in response to a train traversing said stretch, a stick circuit for said approach locking

relay controlled in part by a train approaching the stretch, and a pick-up circuit for said approach locking relay including a front contact of the relay for said track circuit.

5 12. In combination, a section of railway track including a track switch, an approach locking relay, means for preventing operation of said switch unless said relay is energized, a track circuit including a track relay connected across the 10 rails of said section, auxiliary means for detecting the entrance of a train into said section independently of the condition of said track circuit, and a pickup circuit for said approach locking relay closed only when said track relay is 15 deenergized and said auxiliary means indicates that a train is entering said section.

13. In combination, a section of railway track including a track switch, an approach locking relay, means for preventing operation of said switch unless said relay is energized, a track circuit including a track relay connected across the rails of said section, auxiliary means for detecting the presence of a train at a particular point adjacent said switch, and a pickup circuit 25 for said approach locking relay closed only when said track relay is deenergized and said auxiliary means indicates the presence of a train at said point.

14. In combination, a section of railway track 30 including a track switch, an approach locking relay, means for preventing operation of said switch unless said relay is energized, a track circuit including a track relay connected across the rails of said section, auxiliary means independent of said track circuit and including a normally open contact closed only when a train enters said section, and a pickup circuit for said approach locking relay including in series said normally open contact and a back contact of 35 said track relay.

15. In combination, a section of railway track including a track switch, an approach locking relay, means for preventing operation of said switch unless said relay is energized, a track circuit including a track relay connected across the rails of said section, auxiliary means including a normally open contact closed only when a train is present at a particular point adjacent said switch, and a pickup circuit for said approach locking relay including in series said normally open contact and a back contact of said track relay.

16. In combination, a section of railway track including a track switch, an approach locking relay, means for preventing operation of said switch unless said relay is energized, a track circuit including a track relay connected across the rails of said section, auxiliary means including a normally open contact closed only when a train is present at a particular point adjacent said switch, and a checking contact closed only when said first mentioned contact is open, a pickup circuit for said approach locking relay including in series said normally open contact and a back contact of said track relay, and means for indicating when said first mentioned contact is open comprising a normally closed circuit including said checking contact.

17. In combination, a section of railway track 70 including a track switch, an approach locking

stick relay, means for preventing operation of said switch unless said relay is energized, a signal for governing the movement of traffic over said switch, a track circuit including a track relay connected across the rails of said section, auxiliary means independent of said track circuit and including a normally open contact closed only when a train is present at a particular point adjacent said switch, a pickup circuit for said approach locking relay closed only when said contact is closed and said track relay is deenergized, and a stick circuit for said approach locking relay including its own front contact and a contact closed only when said signal is in its most restrictive condition.

18. In combination, a section of railway track including a track switch, a signal for governing the movement of traffic into said section, approach locking means for preventing operation of the switch provided the signal has been cleared and a train is approaching within a predetermined distance of the switch, a track circuit including a track relay deenergized when a train enters said section, auxiliary means independent of said track circuit for detecting the entrance of a train into said section, and means for releasing said locking effective only when said track relay and said auxiliary means both indicate that the train has passed the signal and has entered said section.

19. In combination, a section of railway track, a track switch in said section, a switch machine for operating said switch, a stick relay which must be energized to permit control of said switch machine, a track circuit extending the entire length of said section and including a track relay, a track device in said section but separate from said track circuit to manifest the presence of a train in said section, and a pickup circuit for said stick relay including in series a back contact of said track relay and a normally open contact of said track device.

20. In combination, a section of railway track, a switch associated with said section, a signal for controlling traffic movements over said switch, control means for said signal, a stick relay for controlling the operation of said switch, a detector track circuit extending the entire length of said section and including a track relay, a track device separate from said track circuit and controlled by traffic conditions in said section, a pickup circuit for said stick relay including in series a normally open contact of said track device and a back contact of said track relay, and a stick circuit for said stick relay controlled by said signal control means.

21. In a control system for railroads, a track switch, signals governing traffic over said track switch, locking means normally effective to prevent operation of said track switch after said signals are caused to indicate stop, a detector section having a track relay, a track device in said detector section but separate from said track circuit to indicate the presence of a train in said section, and means causing said locking means to be ineffective to prevent operation of said track switch if both said track relay and said track device indicate the presence of a train.
